FINGER RING

Daniel Shiman, Maplewood, N.J., assignor to Shiman Industries Inc., Newark, N.J.

Filed Apr. 30, 1971, Ser. No. 139,300

Term of patent 14 years

Int. Cl. D11—01

U.S. Cl. D45—10

FIG. 1 is a view in perspective of a 3-stone finger ring showing the ornamental design of the invention;

FIG. 2 is a side elevational view of the finger ring of FIG. 1;

FIG. 3 is an end elevational view of the ring of FIG. 1;

FIG. 4 is a top plan view of the ring of FIG. 1;

FIG. 5 is a top plan view of another embodiment of the ring in accordance with the design of the invention and having one stone;

FIG. 6 is a top plan view of another embodiment of the ring in accordance with the design of the invention and having two stones;

FIG. 7 is a top plan view of another embodiment of the ring in accordance with the design of the invention and having four stones;

FIG. 8 is a top plan view of another embodiment of the ring in accordance with the design of the invention and having five stones.

I claim:

The ornamental design for a finger ring, as shown and described.
